United States Patent Office

Des. 177,029
Patented Mar. 6, 1956

177,029

AIRPLANE

Eugene C. Frost, Burbank, and Albert J. Lechner, North Hollywood, Calif., assignors to Lockheed Aircraft Corporation, Burbank, Calif.

Application December 13, 1954, Serial No. 33,526

Term of patent 14 years

(Cl. D71—1)

FIG. 1

FIG. 2

Figure 1 is a top perspective view of an airplane showing our new design;

Figure 2 is a front elevational view thereof;

Figure 3 is a top plan view thereof; and

Figure 4 is a side elevational view thereof.

The essential features of my design reside in the portions shown in full lines.

We claim:

The ornamental design for an airplane, as shown and described.
